4 Claims. (Cl. 330—205)

This invention relates to amplifier circuits and more particularly to improved amplifier circuits wherein the configuration is such that variations in electron tube heater filament voltages are effectively balanced out to prevent their causing drift in the amplifier.

In electric signal amplifier circuits, particularly in high gain amplifier circuits using electron tubes of the type having heater filaments, variations in voltage across the heater filaments, such as caused by changes in power supply voltages, or changes in resistive values of the filaments themselves, result in undesirable drift effects in circuit operation. This may be seen, for example, by visualizing a small increase in average voltage across the filament of the first stage of a multistage high gain amplifier. The increased voltage results in a hotter filament with increased electron emission which, in turn, tends to cause a decrease in voltage at the plate. The resulting decrease in plate voltage of the first stage may acquire a seriously large magnitude at the amplifier output due to amplification in successive amplifier stages.

Pursuant to the present invention, this problem has been overcome by a novel amplifier circuit arrangement which also achieves other desirable features and advantages. Among these other features and advantages are the achievement of a relatively simple, inexpensive and reliable circuit arrangement which is self-contained and in itself automatically compensates for the filament voltage variations to thereby prevent to the above-mentioned undesired drift.

Accordingly, a primary object of the present invention is the provision of an amplifier substantially free of drift caused by variations in filament voltage.

Another object is the provision of an amplifier having a self-contained circuit arrangement for automatically compensating for filament voltage variations.

And a further object is the provision of a multistage high gain amplifier having a reliable yet relatively simple and inexpensive circuit configuration which automatically compensates for variations in the filament voltage.

These and other objects, features and advantages of the invention are achieved generally in an amplifier circuit of the type having a heater filament amplifier tube, with the filament coupled across the positive and negative terminals of a filament power source, by providing a circuit coupled to the control grid and in responsive relation to the voltage changes of the filament for effecting a grid voltage change which tends to balance out the effect of the filament voltage change.

By providing a resistive voltage divider circuit across the filament voltage source and coupled at a properly proportioned point to the grid, a simple inexpensive arrangement for automatic compensation of filament change is thereby achieved. By making the resistive circuit in the form of a voltage divider chain with one of the resistors in the chain being a variable resistor, simplicity in adjusting balance setting is thereby achieved.

These and other features, objects and advantages of the invention will become more apparent from the following description taken in connection with the accompanying drawing of a preferred embodiment of the invention and wherein:

The single FIGURE is a schematic drawing of a high

2

gain amplifier made in accordance with the present invention.

Referring to the multistage high gain amplifier illustrated in the figure, in more detail, there are three amplifier stages, 10, 12 and 14 having anodes 16, 18 and 20 respectively coupled through resistors 22, 24 and 26 to the positive terminal of a power source such as a battery 28 having a negative terminal coupled to ground. The amplifier stages 10, 12 and 14 also have screen grids 30, 32 and 34 respectively coupled to the positive terminal of grid biasing power source such as a battery 36. The amplifier stages 10, 12 and 14 have control grids 38, 40 and 42 and heater filaments 44, 46 and 48 respectively. The respective stages are coupled in cascade with the plate 16 of the first stage 10 being connected through a resistor 50 to the control grid 40 of the second amplifier stage 12 which has its plate 18 coupled through a resistor 52 to the control grid 42 of the third or output amplifier stage 14. The plate 20 of the third amplifier stage 14 is coupled to an output terminal 54. Control grids 40 and 42 are also coupled to the negative terminal of a source of biasing potential such as a battery 56 having a positive terminal coupled to ground. A signal input terminal 58 is coupled through a resistor 60 to the control grid 38 of the first amplifier stage 10. The control grid 38 is also coupled through a chain of biasing resistors 62, 64 and variable resistor 66 to ground. A feedback line 68 from the plate 20 of the output stage 14 is coupled through a resistor 70 and resistor 62 preferably of high resistive value to the control grid 38 and the first amplifier stage 10.

The heater filaments 44 and 46 of the first two amplifier stages 10 and 12 are coupled in series across a power source such as a battery 72. The positive terminal of filament heater battery 72, is also coupled through a variable resistor 74 and fixed resistor 76 to the input terminal 58. The input terminal 58 is also coupled through a resistor 78 ground. It will be noted that the variable resistor 74, fixed resistors 76 and 78 provide a voltage divider chain connected across the filament battery 72 with the input terminal 58 being coupled to the voltage divider chain between the resistors 76 and 78. Also the variable resistor 74 and fixed resistors 76 and 60, 62, 64 and variable resistor 66 provide another voltage divider chain with control grid 38 of the first amplifier stage 10 being coupled to the voltage divider chain between resistors 60 and 62. These two voltage divider chains are both in effect coupled across the filament power source 72 and designed as will be hereinafter explained to provide compensating voltage changes in the control grid 38 for variations in voltage which may occur across the heater filament 44.

In the operation of the FIG. 1 high gain amplifier, input signals from the input terminal 58 will appear through resistor 60 at the control grid 38 of the first amplifier stage 10 thereby through resistor 50 at the control grid 40 of the second amplifier stage 12 and similarly through the resistor 52 at control grid 42 of the third amplifier stage 14, from the plate 20 of which they will appear at the output terminal 54 suitably amplified in intensity. However, a problem which exists in conventional amplifier circuits of this nature is that in the event the voltage across the heater filament 44 varies for any reason, such as variations in voltages from the power source 72 or changes in resistive values of the heater filament 44 or heater filament 46, a corresponding fluctuation or drift occurs at the plate 16 of the amplifier stage 10. Such drift becomes increasingly serious as it becomes amplified in the successive amplifier stages 12 and 14. For example, if the voltage across the heater filament 44 increases, more current will flow through the filament 44 thereby increasing its temperature. Such

increased temperature of the filament 44 increases the electron emissivity of the filament thereby increasing the electron flow to the plate 16 which, in turn, tends to cause a drop in voltage at the plate 16. However, in the present instance applicant's above described voltage divider chain construction across the filament power source 72 effectively compensates for such increased electron flow tendency from the filament 44 by correspondingly regulating the voltage between the control grid 38 and filament 44. This may be seen by assigning exemplary values to the respective resistors as follows: variable resistor 74—1,000 ohms, resistor 76—5,300 ohms, resistor 78—3,300 ohms, resistor 60—47,000 ohms, resistor 62—1 megohm, resistor 64—3,300 ohms and resistor 66—100,000 ohms. Now assuming a voltage of 2.8 volts across the filament battery 72, the variable resistor 74 may be adjusted to provide a voltage at the input terminal 58 of approximately 1.02 volts and a voltage at the grid 38 of .96 volt. If for some reason the voltage across the filament battery increased, $\frac{1}{2}$ of that increase would appear across the filament 44 and $\frac{1}{2}$ across the filament 46. On the other hand because of the values of voltage divider resistors 74, 76 and 78 a much smaller increase than the abovementioned $\frac{1}{2}$ would occur at the input terminal 58. Because of the voltage divider chain resistors 60, 62, 64 and 66 an even smaller change than that at the input terminal 58 would appear at the control grid 38. It has been found that for the present configuration the proportion values of resistors is such that the change at the control grid 38 caused by the fluctuation of the voltage across the heater filament 44 is just sufficient to provide a relative voltage between control grid 38 and filament 44 to make the control grid 38 look sufficiently more negative to the average filament 44 voltage to just compensate for and prevent the increased electron flow which would otherwise occur from increased temperature of the filament 44. While these resistor values have been found to satisfactorily compensate for such fluctuations in the present embodiment, they are cited here by way of illustration only and other proportions and values may be assigned for other amplifier conditions by using the principles and concepts here disclosed. Adjustment of variable resistor 66 provides a suitable arrangement for varying the gain of the amplifier stage 10. Adjustment of variable resistor 74 provides a rapid and suitable arrangement for the finding of the initial compensating setting for the voltage divider chain across the filament power source 72.

This invention is not limited to the specific construction and operation herein described as equivalents will suggest themselves to those skilled in the art.

What is claimed is:

1. In an amplifier stage, the combination of at least two active electrodes, including a filament-type cathode and a control grid, a resistance chain with the control grid coupled through the resistance chain to ground, a source of uni-directional electric energy in the stage, the source having a pair of terminals and being arranged for heating the cathode and having one of the terminals coupled to ground, and resistance means coupling said

other terminal to a point on the voltage divider chain such that variations in voltage across the source of uni-directional electric energy will cause proportional corrective voltage changes at the grid to maintain a substantially constant current flow in the stage.

2. In an amplifier stage, the combination of at least two active electrodes, including a filament-type cathode and a control grid, a resistance chain with the control grid coupled through the resistance chain to ground, a single battery in the stage coupled across the filament and having one side coupled to ground, and variable resistor means coupling the other side of the battery to a point on the voltage divider chain such that variations in voltage across the battery will cause proportional corrective changes at the grid to maintain a substantially constant current flow in the stage.

3. In an amplifier circuit, the combination of a first and second amplifier stage, including a filament-type cathode having a heater and a filament control grid in each stage with the control grid of the second stage coupled to the output of the first stage, a resistance chain with the control grid of the first stage coupled through the resistance chain to ground, a source of uni-directional electric energy and having a pair of terminals with one of the terminals coupled to ground, the filaments coupled in series across the uni-directional source of electric energy, a voltage divider resistor chain coupled across the uni-directional source of electric energy in parallel with the filaments, and resistor means coupling the other terminal to a point on the divider chain such that variations in voltage across the source of uni-directional electric energy will cause corrective voltage changes at the first grid to maintain a substantially constant current flow in the stages.

4. In an amplifier circuit, the combination of a first and second amplifier stage, including a filament type cathode and a control grid in each stage with the control grid of the second stage coupled to the output of the first stage, a resistor chain with the control grid of the first stage coupled through the resistor chain to ground, a battery having positive and negative terminals, the filaments coupled in series across the battery and the negative terminal coupled to ground, and resistor means coupled to the positive terminal of the battery and to a point on the resistor chain such that variations in voltage across the battery will cause corrective voltage changes at the first grid to maintain a substantially constant current flow in the stages.
